UNITED STATES PATENT OFFICE.

GEORGE S. VON WEDELSTAEDT, OF CHICAGO, ILLINOIS.

RECEPTACLE FOR LIQUID OR POWDERED SOAP.

SPECIFICATION forming part of Letters Patent No. 761,801, dated June 7, 1904.

Application filed November 4, 1902. Serial No. 130,039. (No model.)

To all whom it may concern:

Be it known that I, GEORGE S. VON WEDELSTAEDT, a citizen of the United States, and a resident of Chicago, in the county of Cook and State of Illinois, have invented certain new and useful Improvements in Receptacles for Liquid or Powdered Soap, of which the following is a specification.

My invention relates to receptacles or containers for liquid or powdered soap or other commodities which it is desired to retain and use in limited quantities at various points. It is especially adapted to be utilized in hospitals and operating-rooms where the surgeons, physicians, and attendants are obliged to frequently cleanse the hands and arms of infectious impurities dangerous to the health of those with whom they might come in contact. In such institutions the indiscriminate use of soap by those engaged in surgical work has frequently resulted seriously; but, as will be hereinafter set forth, with my improved receptacle the liability to such contamination is minimized, if not entirely eliminated.

My invention is fully illustrated in the accompanying drawings, in which—

Figure 1 represents the receptacle as it is set up ready for use, and Fig. 2 is a sectional elevation of the lower part of same with the valve open.

A is the receptacle proper, provided with a removable cover *a* and having a converging nozzle *a'*. In the lower end of this nozzle are cut one or more curved discharge-openings *a''*, giving it a crenulate appearance.

B is a plug-shaped valve fitting into the nozzle *a'*. It is bored through its longitudinal center and tapped to receive the screw-threaded valve-stem C, to which is secured the ball or globoid operating-head D. The lock-nut *c* serves to prevent screw C or valve-stem from turning during the operation of the device, and to regulate the height to which the valve may rise.

The operation is as follows: When the receptacle A is secured in a vertical position, as shown, ready for use, it is evident that the valve B will be seated in nozzle *a'* by gravity and held firmly on its seat by the weight of the liquid soap or other substance with which

the receptacle is filled. In this position the ball D is held at a short distance below the end of nozzle *a'*. When it is desired to allow a small portion of soap to escape, the ball is pressed upward against the end of the nozzle, 55 in which position the crenulate end of the nozzle will allow the soap to flow freely over the surface of the ball, spreading thereover and clinging thereto by the laws of capillarity and surface tension until at its lowest point 60 or apex it reaches the hand of the operator and diffuses thereover, the ball resting meanwhile against the salients of the crenulations. When sufficient soap has thus been discharged, the operator removes his pressure on ball D, 65 when the valve B will be seated, as at first described, and the flow of soap checked. The valve-stem C is of sufficient length to allow of a considerable variation in the travel of the valve B from its seat, and it is evident that 70 by the adjustment of this stem C the stroke of the valve may be so regulated as to permit either a large or small quantity of soap to be discharged in a given time. The sides of the receptacle and nozzle converge to facilitate 75 the discharge of the contents by gravity.

From the foregoing description and accompanying drawings it will be readily seen that no portion of the contents of the receptacle except that actually used comes in contact with 80 the hands of the user, and, further, that the action of the contents in flowing around the ball is such as to cleanse it from any adhering impurities at each operation, since in accordance with the laws above mentioned it forms 85 a complete film over the whole surface of the ball and continues to drip from its lowest point or apex after it is released and the valve closed until the remainder left beneath said valve on its closure is completely exhausted.

Any suitable material may be used in the construction of the receptacle, valve, or other parts, and the apparatus may be held in place by any desired form of support adapted to maintain it in an upright position.

Having thus described my invention, what I claim as new, and desire to secure by Letters Patent, is—

1. In a receptacle for liquids or powdered solids, the combination with the body, of a

converging nozzle at the base thereof, having a crenulate lower edge, a tapering valve for said nozzle, a valve-stem extending from the valve through the discharge-opening, and a 5 globoid operating-head attached to the end of the valve-stem and adapted to be closed up against the salients of the crenulations in opening the valve, and to present a complete unbroken surface for capillary action to the contents in their flow, whereby they form a film thereover and discharge at the lowest point or apex thereof.

2. In a receptacle for liquids or powdered solids, the combination with the body of a 15 converging nozzle at the base thereof having a crenulate lower edge, a tapering valve for said nozzle, a threaded valve-stem screwed into said valve, a lock-nut therefor, and a globoid operating-head attached to the end of the 20 valve-stem and adapted to be closed up against the salients of the crenulations in opening the valve, and to present a complete unbroken surface for capillary action to the contents in

their flow, whereby they form a film thereover and discharge at the lowest point or apex 25 thereof.

3. In a receptacle for liquids or powdered solids, the combination with the body, of a converging nozzle at the base thereof, having a crenulate lower edge, a tapering gravity- 30 valve for said nozzle, exposed to the weight of the contents of said body, a valve-stem extending downward from said valve through the discharge-opening of the nozzle, and a globoid head attached to the end of the valve-stem and 35 adapted to be closed up against the salients of the crenulations to open the valve, and to present a complete unbroken surface for capillary action to the contents in their flow, whereby they form a film thereover and discharge at 40 the lowest point or apex thereof.

GEORGE S. VON WEDELSTAEDT.
